UNITED STATES PATENT OFFICE

165,307

PORTABLE STEAM BOILER

Robert A. Sharp, Milwaukee, Wis.

Application May 11, 1951, Serial No. 15,133

Term of patent 14 years

(Cl. D81—2)

To all whom it may concern:

Be it known that I, Robert A. Sharp, a citizen of the United States residing at Milwaukee, in the county of Milwaukee and State of Wisconsin, have invented a new, original, and ornamental Design for a Portable Steam Boiler, of which the following is a specification, reference being had to the accompanying drawings, forming part thereof.

Figure 1 is a perspective view of a portable steam boiler embodying my new design;

Figure 2 is an end view thereof; and

Figure 3 is a side view thereof.

The dominant features of my design reside in those portions thereof shown in full lines.

I claim:

The ornamental design for a portable steam boiler, as shown and described.

ROBERT A. SHARP.
